UNITED STATES PATENT OFFICE

2,278,844

COOLING MEANS FOR DISCHARGE LAMPS

Victor James Francis, North Wembley, and
George Hulbert Wilson, Wembley Park, England, assignors to General Electric Company, a corporation of New York

Application September 11, 1940, Serial No. 356,390
In Great Britain September 13, 1939

2 Claims. (Cl. 176—122)

Our invention relates to apparatus for producing light of the type wherein the source of light is a high-pressure metal-vapor electric discharge lamp subject to forced gas cooling in operation and wherein the leads to the electrodes of the lamp are carried in sealing stems projecting from the envelope of the lamp.

The lamps used in apparatus of this type usually have approximately spherical envelopes and are adapted in full operation to dissipate 1 kilowatt or more with a pressure of metal vapor within the envelope of 5 atmospheres or more.

In such apparatus, of which optical projection apparatus is a typical example, it is often difficult to arrange the forced gas cooling means so that it does not obstruct the light emitted from the lamp in the direction required and so that the lamp can be easily and accurately positioned relative to the rest of the apparatus. The object of this invention is to provide an arrangement in which the forced cooling means is adapted simultaneously to support and cool the lamp without unduly obstructing the light emitted from it and which enables the lamp to be easily and accurately positioned relative to the rest of the apparatus.

According to the invention in apparatus of the type specified the said forced cooling means comprises at least one hollow tube fitting over a sealing stem of the said HPMV lamp so that gas forced through the tube is directed over the envelope of the lamp, and the lamp is supported by the said sealing stem from the said tube or from a member supporting the said tube and is positioned relative to the rest of the apparatus by means supporting the said tube or member.

Preferably the lamp is in this manner supported by, and cooled at, each sealing stem, of which there are usually two.

In the drawing accompanying and forming part of this specification an embodiment of the invention is shown in a side elevational, partly sectional view.

Referring to the drawing the high pressure discharge lamp comprises a sealed, spherical envelope 1 of vitreous material, such as quartz or glass having a high softening temperature. Said envelope 1 has a starting gas therein, such as argon, at a pressure of about a centimeter and a quantity of mercury the vapor of which is luminosity producing during the operation of the lamp and has a vapor pressure of 5 atmospheres or more. Two elongated sealing stems 2 project from opposite sides of the envelope 1. Each sealing stem abuts against one end of a hollow metal

5 tube 3 and is secured to it by means of extensions of the current leads 4 to an electrode 5 of the lamp. The leads 4 consist of a plurality of thin metal strips, such as molybdenum strips, having 10 tungsten wires fastened thereto. The leads 4 are arranged in spaced relation between an inner tube or cylinder of quartz and an outer quartz tube. These elements are fused together to form 15 a mechanically strong, gas tight sealing stem. The external end of each of the leads 4 is clamped between the metal tube 3 and the metal ring 6. At its other end each tube 3 is connected by a flexible pipe 7 to a reservoir of compressed air (not shown) from which air is passed into the 20 tube as indicated by the arrow; the air passes out of the tube 3 through orifices 8 and is directed over the envelope of the lamp by means of a metal tube 9 which fits over the sealing stem 2 and is supported and insulated from the tube 3 by means of a rubber stopper 10.

25 The arrangement is supported, and the lamp thereby positioned relative to the rest of the apparatus (not shown) by means of metal clamps 11 supporting the tube 3. These tubes and the clamps 11 act as extensions of the leads 4 to the electrodes 5 and connections to the source of electric supply (not shown) are taken from the arms 12 of the clamps.

30 It will be seen that in this embodiment each tube 9 is a said hollow tube fitting over a sealing stem, each tube 3 is a said member supporting a said hollow tube and also the lamp, and each clamp 11 is a said means supporting a said tube or member as stated in the foregoing statement of invention.

35 In another embodiment of the invention the HPMV lamp is supported directly by its sealing stems from hollow tubes, such as 9 in the accompanying drawing, by means of rubber stoppers.

40 Air is pressed through the tube by means of bores in the said stoppers and is directed by the tubes over the lamp. The arrangement is supported and the lamp positioned by means of clamps directly supporting the said tubes, and 45 connections to the source of electric supply are taken directly from the leads emerging from the sealing stems.

What we claim as new and desire to secure by Letters Patent of the United States is:

50 1. In combination, a high pressure gaseous electric discharge lamp of the type requiring forced cooling for proper operation and a cooling system therefor, said lamp having a spherical envelope and elongated exposed stems projecting therefrom, said stems being mounted in opposing

positions on said envelope, said cooling system comprising a metal tube removably fastened to one of said stems and another tube supported by said metal tube about said stem and said metal tube and terminating adjacent said envelope, the wall of said metal tube being perforated at the part thereof in said surrounding tube to permit the flow of cooling gas into said surrounding tube and directly over the surface of said stem and said envelope.

2. In combination, a high pressure gaseous electric discharge lamp of the type requiring forced cooling for proper operation and a cooling system therefor, said lamp having a spherical envelope and elongated exposed stems projecting 15

therefrom, said stems being mounted in opposing positions on said envelope, said cooling system comprising a metal tube removably fastened to one of said stems and another tube supported by 5 said metal tube about said stem and said metal tube and terminating adjacent said envelope, the wall of said metal tube being perforated at the part thereof in said surrounding tube to permit the flow of cooling gas into said surrounding tube and directly over the surface of said stem and 10 said envelope, said metal tube being a current lead for said lamp.

VICTOR JAMES FRANCIS.
GEORGE HULBERT WILSON.
